United States Patent Office

Des. 178,958
Patented Oct. 16, 1956

178,958

CONTROL UNIT FOR SELF-CONTAINED AIR CONDITIONING UNIT

Lurelle Guild, New York, N. Y., assignor to Carrier Corporation, Syracuse, N. Y., a corporation of Delaware

Application June 1, 1955, Serial No. 36,319

Term of patent 14 years

(Cl. D62—4)

FIG. 1

FIG. 2

Figure 1 is a front elevation of a control unit for self-contained air conditioning unit embodying my new design with the access cover in closed position; and

Figure 2 is a perspective view of the unit with the cover in an open position.

I claim:

The ornamental design for a control unit for self-contained air conditioning unit, as shown.
